(57) **CLAIM**

The ornamental design for a modular mat with size adjustability as shown and described.

DESCRIPTION

FIG. 1 is a top side perspective view of the modular mat with size adjustability showing our new design;

FIG. 2 is a left side thereof;

FIG. 3 is a right side thereof;

FIG. 4 is a front side view thereof;

FIG. 5 is a rear side view thereof.

FIG. 6 is a top view thereof;

FIG. 7 is a bottom view thereof; and,

FIG. 8 is a bottom side perspective view thereof.

The dash broken lines illustrating structure in the drawings form no part of the claimed design.
